UNITED STATES PATENT OFFICE.

EUGENE ORA DANIELS, OF TOLEDO, OHIO.

GAS AND VAPOR BURNER.

Application filed February 19, 1923. Serial No. 619,865.

To all whom it may concern:

Be it known that I, EUGENE O. DANIELS, a citizen of the United States, residing at Toledo, in the county of Lucas and State 5 of Ohio, have invented certain new and useful Improvements in Gas and Vapor Burners, of which the following is a specification.

This invention relates to certain new and 10 useful improvements in gas and vapor burners for furnaces, steam boilers, stoves and the like, the object being to provide a burner which is extremely simple and cheap in construction, and of ease in installing and 15 removing when occasion requires a change of the fuel as from gas to coal or other fuel.

A further object of my invention is the provision of a burner which is capable of burning natural or artificial gas, oil vapor 20 or gas, the same being so constructed that it can be used in the ordinary coal burning stove or furnace, steam boiler and the like.

With the above recited objects in view, 25 and others of a similar nature, the invention resides in the construction, combination and arrangement of parts set forth in and falling within the scope of the appended claims.

30 Figure 1 is a top plan view of a burner constructed in accordance with my invention.

Figure 2 is a vertical, transverse cross 35 sectional view upon the broken line 2-2 of Figure 1 and,

Figure 3 is an elevational view of a modified form of burner head which may be employed in conjunction with this invention.

Referring to the drawing in detail, 5 40 designates the burner manifold, 6 the dome and 7 the burner heads. The manifold 5 is in the form of a single casting including a hollow hub portion 8 and rim 9 the said rim and hub portions communicating with each other through a desirable number of connecting pipes 10. In the casting of this manifold there is occasioned at spaced points upon the outer wall of the rim 9 openings 11, the same being screw threaded for receiving screw threaded filler plugs 12, which 45 carry projecting heads 13 which may be and preferably are of angular form. Communication is established between the hub portion 8 of the manifold and a source of fuel supply through a pipe 14.

55 The dome 6 is in the form of substantially

inverted pan-shaped member and is adapted for positioning over the manifold 5 as more clearly shown in Figure 2, it being understood that the diameter of the side wall of this dome is relatively greater than the similar dimension of the manifold 5 for the purpose of allowing a passage of air between the rim 9 of the manifold and the said side wall of the dome. The pan-shaped dome 6 is formed at its lower end with spaced notches 15, which notches receive the said angular projecting heads 13 of the filler plugs 12.

The top wall of the dome 6 is formed with 70 a plurality of spaced openings 16 adjacent the outer edge of the dome, these openings being surrounded by vertical nipples 17, formed integral with the dome.

The burner heads 7 are of a relatively 75 elongated nature as clearly shown in the two views, the top wall of these heads being formed with a plurality of gas outlet openings 18. Intermediate the ends of the heads the same are formed upon their bottom walls with screw threaded openings 19 for receiving the upper externally threaded ends of pipe sections 20, it being understood that the opposite lower ends of these pipes loosely engage in the said vertical nipples 80 of the dome 6. It is also to be noted that the top wall of the rim 9 of the manifold 5 is formed with gas outlet openings 21 directly beneath each of the openings 16 in said dome 6.

When my burner is arranged as per Figures 1 and 2 it will be apparent that when the gas escapes from the outlets 21 of the manifold this gas will thoroughly mix with the air passing upwardly between the hub and rim portions of the manifold as well as between the side wall of the dome and the outer face of the rim 9, and further, when my burner heads are arranged as in these two figures, the same will extend readily from the center portion of the dome 6, the flame thereby extending upwardly.

In Figure 3 I have shown one of the burner heads 7' as being connected to its pipe 20' through the instrumentality of an elbow connection 22 the purpose of this being to permit the pipes 20' to be inserted within the nipples 17 of the dome 6 for consequently throwing the flame from the burner heads at right angles to the vertical 105 axis of the burner proper.

In view of the above description it is be-

lieved that the advantages and operation of a burner of this type will be readily appreciated by those skilled in the art and although I have herewith shown and described 5 the preferred embodiments of this invention it is nevertheless to be understood that minor changes may be made in the invention without departing from the spirit and scope thereof, as claimed.

10 Having thus described the invention, what is claimed as new, is:—

15 1. In a burner of the class described, a manifold having a gas inlet pipe communicating therewith, a dome supported upon the said manifold in spaced relation thereto, burner heads carried by the dome and removable therefrom, the said manifold being formed with outlet openings and means upon said manifold for supporting said dome.

20 2. In a burner of the class described, a manifold having communication with a source of fuel supply, a dome removably positioned upon said manifold, and burner heads removably carried by the dome, said manifold being formed with gas outlet open-

ings beneath the burner heads of the dome.

3. In a burner of the class described, a manifold comprising a hollow hub and a rim portion communicating with each other through the instrumentality of pipe sections, said rim being formed with gas outlet openings, and a dome removably supported upon the manifold, and burners carried by the dome and in communication 35 with the outlet openings of said manifold.

4. In a burner of the class described, a manifold formed with openings in the side wall thereof as well as openings in the top wall, a source of fuel supply to said manifold, plugs within the said openings in the side wall of the manifold and having integral projecting lugs formed thereon, a dome supported above the manifold and formed with notches for the reception of 40 said plug lugs, and burners carried by the dome and directly above the said openings in the top wall of the manifold.

45 In testimony whereof I affix my signature.

EUGENE ORA DANIELS.
